COAT AND METHOD OF MANUFACTURE

Joseph Haspel, New Orleans, La., assignor to
Haspel Brothers, Inc., New Orleans, La.

Application October 2, 1937, Serial No. 167,058

4 Claims. (Cl. 2—268)

This invention relates to an outer garment of the coat type and the method of manufacturing it.

The object of the invention is to manufacture, in a manner as hereinafter set forth, a coat which will retain its shape and be more slightly in appearance.

A further object of the invention is to provide a coat including a simple, compact, durable, thoroughly efficient means of a form, in a manner as hereinafter set forth, acting as a shoulder pad and sleeve support and coacting with other parts of the garment to provide for the latter retaining its shape and to enhance its appearance.

A further object of the invention is to provide a coat including the means as aforesaid and with such means capable of being expeditiously installed in the coat body at a very nominal addition with respect to the cost of producing the garment not having as a part thereof the said means.

To the above ends essentially and to others which may hereinafter appear, the invention consists of the novel construction, combination and arrangement of parts as will be more specifically described and illustrated in the accompanying drawings wherein is shown embodiments of the invention, but it is to be understood that changes, variations and modifications may be resorted to which fall within the scope of the invention as claimed.

In the drawings:

Figure 1 is an elevation looking towards the outer face of one side of the coat constructed in accordance with this invention and illustrating in dotted lines the means which acts as a shoulder pad and a support for the head of the sleeve of the coat.

Figure 2 is a fragmentary view in elevation looking towards the inner face of the side of a coat constructed in accordance with this invention.

Figure 3 is a section on line 3—3, Figure 1 upon an enlarged scale,

Figure 4 is an elevation of the combined shoulder pad and sleeve head supporting unit forming an element of a coat in accordance with this invention.

Figure 5 is a fragmentary view in elevation looking towards the inner face of the side of a modified form of coat in accordance with this invention and illustrating parts thereof disassembled.

Figure 6 is a fragmentary view in elevation

looking towards the inner face of the modified form of coat in accordance with this invention,

Figure 7 is a section on line 7—7, Figure 1 upon an enlarged scale, and

Figure 8 is an elevation of the combined shoulder pad and sleeve head supporting unit employed in the modified form of coat shown in Figures 5 to 7.

With reference to the drawings and as is well known the body portion of certain forms of coats includes an outer facing 10 which provides the neck, sides, front and back of the coat, a pair of linings 11, only one shown, and each of which is arranged against the inner face of the portions of the facing 10 which provide a shoulder, 15 a part of the front and a side of the coat. The pair of linings 11 have the upper portions of their inner edges connected together by a transverse extending narrow lining 12. One of the shoulders provided by the facing 10 is indicated 20 at 13. One of the armholes of the coat is designated 14 and is provided in the facing 10 and in a part of the lining 11. One of the sleeves of the coat is indicated at 15.

In a coat construction, in accordance with this invention, the edge of the armhole 14 has the major portion of its length enclosed by a binder 16. The ends of the binder 16 are indicated at 17. That portion of the edge of the armhole 14 which is not provided with the binder is indicated at 18. A part of the upper end of the sleeve 15 extends into the binder 16. The shoulder 13 in proximity to its outer edge is secured to the remaining portion of the upper end of the sleeve 15 adjacent the top edge of such portion as at 19. The binder 16 is secured to the facing 10, sleeve 15 and a part of lining 11 by stitching 20.

Arranged between lining 11 and shoulder 13 of facing 10 is a portion of a combined pad and supporting means 21 for the shoulder 13 and the head end of the sleeve 15. The other portion of the means 21 extends into the upper part of the head of the sleeve 15. Secured to the lining 12 and facing 10, adjacent the upper portion 40 of the edge of the armhole 14, as at 22 is one end of a retaining member 23 which encompasses that portion of the means 21 arranged in the head of the sleeve. The member 23 is bent upon itself to provide a fold 24 which has its free end 45 secured to the inner face of the sleeve 15 adjacent the edge of the armhole 14 by the stitching 25. The latter also acts to secure the means 21 with the sleeve 15 and member 23.

With reference to Figures 2 and 4, the means 55

21 is a unit formed of a pair of outer sections 26, 27 and an inner section 28 of pad-like material. The sections 26, 27 project from the section 28 and their projected portions are connected together by the stitching 29. The sections of the means 21 are secured together by a row of stitching 30. The section 26 as well as the section 27 is formed from a piece of fabric which is so shaped to provide the means 21 with a lateral tapered extension 31 merging into the portions 32, 33 of the means 21. The portion 32 is of greater length than the portion 33. The portion 32 has its edge 34 of arcuate contour. The portion 32 has its edge of concave contour. 10 When the means 21 is mounted in position, that side thereof provided with the extension 31 depends below the other side of said means and is arranged in the sleeve head.

With reference to Figures 5 to 8, the coat structure will be the same as that shown by Figures 1 to 4 with this exception that the combined pad and supporting means 35 respectively for the shoulder and sleeve head is formed of a pad section and a support section 36, 37 respectively. 15 The latter is secured to one side of the section 36 and depends from one end thereof as well as extending laterally from each side thereof. One of the extended portions of the section 37 and indicated at 38 is of greater length than the other extended portion 39 thereof. The section 36 is of semi-circular contour and is formed of a pair of strips of fabric 40, 41 having interposed therebetween a strip of padding material 42. The strips 40, 41, 42 are secured together by 20 stitching 43. The section 36 has an arcuate edge 44 and a horizontal edge 45. The section 38 is of oblong contour and formed of a strip of fabric 46 and a strip of padding material 47. The fabric strip 46 is bent upon itself to provide 25 it of U-shape in transverse cross section and the padding material 47 is arranged within the strip 46. The strip 46 and strip 47 are secured together by stitching 48. The section 37 is positioned against the strip 40 of section 36, in 30 proximity to the said horizontal edge 45 and is so arranged relatively to section 37 to provide it to extend in a manner as heretofore set forth. The means 35 is connected to and arranged in 35 position relative to the body and sleeves of the coat in a manner as the means 21 is connected and arranged in position. The means 35 functions for the same purpose as the means 21. The latter as well as the means 35 possesses a soft 40 characteristic.

55 Each of the extensions is to provide a support or padding to the sleeve head at the point toward the front of a sleeve where the latter joins the coat body to thereby produce a rounded effect in the sleeve itself. The action of the 60 arms of the wearer do not crease the supports or paddings provided by the extensions, as whatever creases appear in the fronts of the sleeves caused by the movement of the arms are below and under the extensions.

65 What I claim is:

1. In a method of manufacturing a coat, the positioning of a pair of oppositely disposed padding and supporting means relative to the shoulders and the heads of the sleeves of the coat, 70 positioning oppositely disposed retainers in en-

compassing relation with respect to the portions of said means constituting the supports for the sleeve heads, securing one end of the retainers to the coat body in proximity to the armholes in the latter securing the other end of the retainers to the inner face of the coat sleeves in proximity to the armholes and simultaneously with the securing of the said other ends of the retainers anchoring the said means with the retainers and sleeves. 10

2. In a coat having a shoulder, an armhole and a sleeve extended from the latter, the combination of means having a portion located at the shoulder to constitute a pad for the latter and a portion extended through the armhole into the sleeve to constitute a support for the head of the latter, a retainer encompassing that portion of said means positioned in the sleeve, stitching securing one end of the retainer to the coat in proximity to the armhole, and stitching securing the other end of the retainer to the sleeve in proximity to the armhole and for anchoring said means, retainer and sleeve together. 20

3. In a coat having a shoulder, an armhole and a sleeve extended from the latter, the combination of means having a portion located at the shoulder to constitute a pad for the latter and a portion extended through the armhole into the sleeve to constitute a support for the sleeve head at the point toward the front of the sleeve 30 where the sleeve joins the body of the coat to provide a rounded effect in the sleeve itself and whereby creases appearing in the front of the sleeve, caused by the movement of the arm are disposed below the extension, a retainer encompassing that portion of said means positioned in the sleeve, stitching securing one end of the retainer to the coat in proximity to the armhole, and stitching securing the other end of the retainer to the sleeve in proximity to the armhole 40 and for anchoring said means, retainer and sleeve together, said means consisting of a substantially semi-circular portion provided with a lateral extension. 35

4. In a coat having a shoulder, an armhole and a sleeve extended from the latter, the combination of means having a portion located at the shoulder to constitute a pad for the latter and a portion extended through the armhole into the sleeve to constitute a support for the sleeve head at the point toward the front of the sleeve where the sleeve joins the body of the coat to provide a rounded effect in the sleeve itself and whereby creases appearing in the front of the sleeve, caused by the movement of the arm are disposed below the extension, a retainer encompassing that portion of said means positioned in the sleeve, stitching securing one end of the retainer to the coat in proximity to the armhole, and stitching securing the other end of the retainer to the sleeve in proximity to the armhole and for anchoring said means, retainer and sleeve together, said means consisting of a semi-circular section and an oblong section extending from the horizontal edge and laterally in opposite directions with respect to the curved edge of the semi-circular section, said oblong section being positioned at one side of the semi-circular section. 60 65
